Attorney, Agent, or Firm—Stevens, Davis, Miller &
Mosher

[57] CLAIM

The ornamental design for kitchen tongs, as shown and
described.

DESCRIPTION

FIG. 1 is a front elevational view of kitchen tongs
showing my new design;

FIG. 2 is a right side elevational view thereof; and
FIG. 3 is a top plan view thereof, as seen along lines
3—3 of FIG. 2.
